THREE FACED CONVERTIBLE DOLL

Frank F. Riforgiate, 12831 Foster Road,
Rossmoor, Calif. 90720

Filed June 5, 1969, Ser. No. 17,525

Term of patent 7 years

U.S. Cl. D34—4   Int. Cl. D21—02

FIG. 1

FIG. 2

FIG. 3

FIG. 4

FIG. 5

FIG. 6

FIGURE 1 is a side view showing three faces of the three faced convertible doll.

FIGURE 2 is a side elevation showing one face of the three faced doll.

FIGURE 3 is a side view showing another face of the three faced doll.

FIGURE 4 is a front elevation illustrating the face as shown in FIGURE 3.

FIGURE 5 is a front elevation of the face shown in FIGURE 2.

FIGURE 6 is a front elevation of the third face of the doll formed by inverting the skirt.

I claim:

The ornamental design for a three faced convertible doll, substantially as shown and described.
